(57) **CLAIM**

The ornamental design for a wireless communication repeater, as shown and described.

DESCRIPTION

FIG. 1 is a perspective view of a wireless communication repeater showing my new design;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a bottom plan view thereof.

The broken lines shown in the views are included for the purpose of illustrating portions of the wireless communication repeater that form no part of the claimed design.
